UNITED STATES PATENT OFFICE.

ANGUS S. MACDONALD, OF GREAT NECK STATION, AND FRANKLIN BOOTH, OF NEW YORK,
N. Y., ASSIGNEES TO THE SNEAD & CO. IRON WORKS, OF JERSEY CITY, NEW JERSEY,
A CORPORATION OF NEW JERSEY.

DESIGN FOR A LAMP-SHADE.

54,642.

Specification for Design.

Patented Mar. 9, 1920.

Application filed August 13, 1919. Serial No. 317,353. Term of patent 7 years.

To all whom it may concern:

Be it known that we, ANGUS S. MACDONALD and FRANKLIN BOOTH, residing at Great Neck Station, county of Nassau, and State of New York, and at New York city, county of New York, and State of New York, respectively, have invented a new, original, and ornamental Design for a Lamp-Shade, of which the following is a specification, reference being had to the accompanying drawings, forming a part thereof.

The design consists in applying ornamentation to one side of the shade depicting war scenes, and ornamentation on the inside of the shade in the nature of emblems or figures, representing peace. When the lamp is not lighted, the war scenes only are visible, but when the lamp is lighted, the representations of peace are projected through the shade giving the effect of peace beginning to shine on the scenes of battle.

The design is particularly adaptable for

use in connection with conical shades, and in Figure 1, we have shown a plan view, the blank from which such a shade is made, said blank showing both the war scenes and the representations of peace as they would be seen when the lamp is lighted. It will be noted that the two female figures representing peace appear in the clouds. Fig. 2 is a diagrammatic view similar to Fig. 1, roughly indicating the war scenes and showing the appearance of the clouds when the lamp is not lighted. Fig. 3 is a view representing the figures on the opposite side of the shade behind the clouds.

What we claim is:—

The ornamental design for a lamp shade as shown and described.

In testimony whereof we have hereunto signed our names.

ANGUS S. MACDONALD.
FRANKLIN BOOTH.
